UNITED STATES PATENT OFFICE.

JOHN HASENPFLUG, OF GENEVA, OHIO, ASSIGNOR TO THE CHAMPION SAFETY LOCK COMPANY, OF GENEVA, OHIO, A CORPORATION OF OHIO.

DOOR-CLOSING MECHANISM.

1,181,075.

Specification of Letters Patent.

Patented Apr. 25, 1916.

Application filed April 29, 1909. Serial No. 492,827.

To all whom it may concern:

Be it known that I, JOHN HASENPFLUG, a citizen of the United States of America, and a resident of Geneva, in the county of Ash-5 tabula and State of Ohio, have invented certain new and useful Improvements in Door-Closing Mechanism, of which the following is a specification.

My invention relates to improvements in 10 door checks and springs, and is shown herein, in connection with a liquid door check operating against a suitable fluid-pressure medium, such as oil or glycerin, although said invention does not relate to this feature, 15 but rather to the spring-actuating mechanism and the means for adjusting the same.

In certain types of door checks and springs which have been sold in the past, the provision of a double acting spring 20 wound alternatively from either end has involved the connection of the actuating lever-arm with exterior members upon the cover as by ratchet mechanism or engaging parts which require adjustment. These, being situated exterior of the casing, are liable 25 to gather dirt, to be misadjusted or tampered with, and not infrequently are broken.

In my improved device, I have simplified the construction by connecting only the 30 spindle with the lever arm, and have associated with said spindle, suitable clutch mechanism adapted to wind the spring in either direction. In connection with one of said clutch members, which for the sake of 35 simplifying the parts, the casing-cover preferably forms one element, I have provided adjusting means, whereby the tension of the actuating spring may readily be regulated. Details of these improvements will best be 40 gathered by making reference to the accompanying sheet of drawings, wherein:—

Figure I illustrates in vertical and longitudinal cross section the preferred embodiment of my invention. Fig. II shows the 45 device with the spring casing partially broken away and the spring in section. Fig. III is a view of a modified type of door closing mechanism. Figs. IV and V respectively are top and bottom views of the upper clutch member of the preferred embodiment. Fig. VI is a top view of the adjusting means and cover of Fig. III. Fig. VII shows in perspective the middle clutch member. Fig. VIII shows the bottom clutch 50 member employed in both types of door 55

spring; and Fig. IX is a view partially broken away illustrating the adjusting means provided for the upper clutch member in the device of Fig. III.

Throughout each of the several figures of 60 the drawings, I have indicated similar parts by the same character of reference.

With the exception of the upper clutch member and its adjusting means, the different types of device herein shown are exactly 65 the same. The checking mechanism proper is of any suitable type and may well conform to that shown in the patent to Blount, No. 458,357, August 25, 1891.

The casing comprises an upper spring 70 casing *a*, and a lower cylindrical member *b*, wherein piston *c* is adapted to be actuated. The latter is provided with one or more ball-valves *c'* opening outwardly, and the piston is connected directly with a crank 75 arm *d'* upon the spindle *d*, by means of a link *c''*. The escape of the fluid from in front of the piston is regulated by a screw *b'* controlling the passage *b''*, while the spindle is adapted to be rotated in either 80 direction by means of a lever-arm (not shown) suitably connected with a door; all as will be well understood by those conversant with the art.

Within the spring chamber *a* is a helical 85 spring *e* having hooked ends at the top and bottom, and the cross section of said spring-body preferably is oval. The spindle passes through the center of the spring chamber and a suitable gland or packing *d''*; and is 90 squared throughout its upper portion to receive, both the actuating clutch member or dog *f*, and the lever arm for rotating said spindle.

At the bottom of the spring chamber and 95 engaging the lower end of the spring *e*, is located the bottom clutch member *g*, which normally is withheld from rotation in a clockwise direction, by means of a stop or stud *g'* screwed into the floor of the spring 100 chamber. The lug *f'* upon the dog *f*, engages a corresponding lug or extension *g''* upon the bottom clutch member, and is adapted to rotate the same in a counterclockwise direction against the tension of the 105 spring *e*. In accordance with my improved construction, the dog *f* alone rotates in either direction with the spindle, while the lower clutch member *g* is rotatably mounted about the stuffing box, and the rotatable clutch 110

- member *h* and cover *j* of the upper clutch mechanism, are loose upon and permit the free rotation of the spindle therein in a counterclockwise direction.
- 5 The upper clutch mechanism, as stated, preferably constitutes as well, the cover or closure-part for the spring chamber, and includes adjusting means for the spring, as will now be described in detail. Within the 10 bore of the upper clutch member *h* (Fig. I), is provided a spring *i* which encircles the spindle *d*, and is adapted to rotate said clutch member *h* in a counterclockwise direction with respect to the cover, to the end that 15 a release of the screw *h'* forming an adjusting detent for effecting the adjustment of spring *e*, will hold the clutch member in position against stop *a'* upon the casing, and permit the cover *j* to be turned, in order to 20 secure proper tension upon said spring *e*. This is accomplished by rotating said cover through a greater or less arc to increase (or diminish), as required, the distance between the lug *j'* engaging the upper end of the 25 spring and the extension *h''* upon said clutch member *h*. At the left-hand end of dog *f*, is provided an upper extension or lug *f'*, which is adapted to engage the extension or fin *h''* upon the member *h*, carrying 30 the arm or extension *h''*, and thereby serving to rotate said member and the connected cover *j* as a whole against the tension of spring *e*, when the spindle is turned in a 35 clockwise direction.
- With reference to the modification shown in Fig. III, it is seen that the principles of operation are exactly the same as with the device already explained, except that a separate adjusting member *k* passes through 40 the cover *j*, and engages the upper clutch member *h*. These two parts are respectively formed with engaging recesses and shoulders *k' k''*, which permit of their assemblage in the position shown in Fig. III 45 upon either side of the cover, with the upper clutch member *h* in engagement with the middle clutch member *f*. The adjustment in an analogous manner, is effected by rotating the supplemental cover or adjusting 50 member *k* with respect to cover *j*, which in turn rotates the clutch member *h* with respect to lug *j'* upon cover *j*, whereupon the parts are secured together by means of the pin *k''* engaging suitable holes arranged in 55 an arc upon the cover *j*. Accordingly, with either of these types of spring adjustment, it is seen that merely by turning the cover *j* by means of a suitable spanner engaging lugs *l* thereon, for example, in a clockwise 60 direction, meanwhile retaining the clutch member *h* with its arm or extension *h''*, in engagement with the lug *a'* upon the casing, will serve to secure the relative adjustment, and increase or diminish the arc between 65 said arm *h''* and the lug *j'* attached to the

upper end of spring *e*. The parts are held in the desired position of adjustment and the spring thereby placed under the required initial tension, by means of a suitable screw or pin, as indicated.

Inasmuch as I have provided no small exterior parts for engagement with the lever arm, but have retained the operative mechanism entirely within the spring casing, and as a part of the clutch mechanism, it is apparent that my improved device is not likely to be interfered with or broken, while the adjustment is so simple and direct, that no difficulty is experienced in altering the tension of the spring.

Having now explained the preferred embodiments of my invention, I claim as new, and desire to secure by Letters Patent, the following:

1. In a door check and closer, the combination with suitable checking means, of a spindle connected to actuate the same when rotated in either direction, a casing, a spring therein indirectly connected at either end with said spindle, clutch mechanism for effecting such connection, comprising a central dog and upper and lower clutch mechanism adapted to be alternatively actuated thereby and connected respectively with the corresponding ends of said spring; a portion of the upper clutch mechanism constituting a cover for the casing and having an associated adjusting arm, and stops upon the casing respectively engaging the lower clutch member and the adjustable arm, substantially as set forth.

2. The combination in a door-closing mechanism, with an inclosed casing, of a rotatable spindle therein, a spring connected to react respectively against the casing and the spindle, and an adjustable connection for one end of said spring, comprising a rotatable attaching-part positioned wholly within the casing and connected with the spring, a co-acting arm movable with relation thereto, means for retaining it in its position of adjustment, and an internal stop within the casing adapted to be engaged by said arm, substantially as set forth.

3. In a door check and closer, the combination with suitable checking means including a piston, of a spindle connected to the piston to actuate the same, a spring connected to said spindle to be actuated thereby, and an adjustment for said spring, comprising a rotatable attaching-part connected with one end thereof, and a co-acting arm rotatably adjustable with respect to the point of connection with the spring, means for retaining said arm in its positions of adjustment, a stop against which the arm normally bears, and a casing wherein said spring, its rotatable attaching part and adjusting arm are positioned substantially as set forth.

4. In door check and closer, the combination with a suitable checking device, of a spindle adapted to actuate the same when rotated in either direction, a casing, a spring 5 therein indirectly connected with the spindle by clutch mechanism, comprising a dog, a lower clutch member connected with the corresponding end of the spring and adapted to be rotated by the dog in one direction, 10 and an upper clutch member, comprising a casing-cover connected with the spring, and an adjusting arm associated with said cover, an adjusting detent therefor, and stops upon 15 the casing adapted respectively to engage the lower clutch member and the arm of said upper clutch member and prevent them from rotating in like directions, substantially as set forth.

5. In an adjusting device for door springs, the combination with a rotatable 20 cover-member connected with the spring and adapted to place the same under tension when rotated in a clockwise direction, of an adjusting arm independently rotatable with respect to said cover-member, an adjusting 25 detent therefor, an independent spring tending to rotate said arm in a counterclockwise direction, and a stop-member adapted to be engaged by said arm, substantially as set forth. 30

Signed at Geneva, Ohio, this 31st day of March 1909.

JOHN HASENPFLUG.
